GAME

Howard N. McDermott, Washington, D. C., assignor of one-half to Mary Elizabeth Elsom, Hendersonville, N. C., and one-half to Estelle A. Betzell, Washington, D. C.

Application November 13, 1934, Serial No. 752,885

11 Claims. (Cl. 273—138)

The invention relates to games and game boards, and has for its object to provide a device of this character in which competing players may drop discs or other objects, and which discs will be deflected from side to side in their downward movement until they are stopped by upwardly and outwardly inclined members projecting from apertures having predetermined value indicia to be computed by the opposing players and slides forming closures for said apertures and adapted to be moved to open position after the computing operation for allowing the disc to pass through the board in which the apertures are disposed to a holding receptacle for the disc.

10 A further object is to provide adjacent the disc receiving apertures, indicia, preferably simulating playing cards, and legends corresponding therewith to the sides of the device and constituting fortune telling subject matter, thereby allowing the device or game to be used for fortune telling.

15 A further object is to provide means whereby the indicia carrying board may be held against bowing incident to warping.

20 A further object is to provide the apertures with disc receiving plates extending upwardly and outwardly therefrom and terminating to the rear of the apertures and disc holding plates slidably mounted on the back of the apertured board and forming a stop for the discs or checks until the disc holding plates are moved after a playing operation.

25 A further object is to provide disc holding plates on the rear of the apertured board and carried by a vertically movable rack slidably mounted on the rear of the board for simultaneously allowing the discs or checks to pass through the apertures.

30 A further object is to provide the apertured board at its lower end with upwardly diverging deflecting flanges at opposite sides of the lower series of apertures for insuring the passage of all checks that may pass the pins into some of the apertures.

35 A further object is to provide the upper end of the frame with an elongated check receiving slot extending the full width at least of the apertured portion of the game board, thereby allowing a wide range of positioning of the checks and consequent skill of the operator in attempts to cause the check or disc to enter chosen apertures.

40 A further object is to provide the slideable rack with a handle member by which it may be easily moved after the completion of plays by competing players.

45

With the above and other objects in view the invention resides in the combination and arrangement of parts as hereinafter set forth, shown in the drawings, described and claimed, it being understood that changes in the precise embodiment of the invention may be made if desired without departing from the scope of the claims.

In the drawings:

Figure 1 is a front elevation of the game board 10 showing the front glass plate broken away to better show the structure.

Figure 2 is a vertical transverse sectional view through the game board.

Figure 3 is a rear elevation of the game board, 15 showing the slideable rack, and the back removed.

Figure 4 is a vertical enlarged transverse sectional view through a portion of the apertured board and showing the same on an enlarged scale.

Figure 5 is a perspective view of a portion of the apertured board, showing the deflecting members around the same.

Figure 6 is a vertical transverse sectional view through the check receiving receptacle.

Figure 7 is a perspective view of a modified board showing one of the apertures wherein the deflecting member in the aperture is stamped from board.

Figure 8 is a top plan view of the board showing 30 the elongated coin slot.

Referring to the drawings, the numeral 1 designates a rectangular shaped casing of the device which comprises a front glass wall 2, an intermediate wall 3, and a rear wall 4. The intermediate wall is preferably formed from laminated wood or metal, and is held in place against warping by a screw 6, threaded through reinforcing strips 7 carried by the inner side of the rear wall 4 and into engagement with transverse reinforcing strips 8 carried by the rear side of the intermediate wall 4 and by threading said screws 6 inwardly the intermediate wall 3 may be forced forwardly so that the guide strips 9, projecting forwardly from the front side of the intermediate wall, will be forced into engagement with the inner side of the front wall 2 as well as the guide pins 10 for rigidly holding the intermediate wall against rearward or forward bowing incident to warping.

Mounted on the front side of the intermediate wall 3 are playing cards 11, having various values and preferably surrounding the apertures 12, through which the checks used for playing the game pass. The playing cards may be printed

directly on the intermediate wall 3 or may be pasted thereon and applicant does not limit himself in this particular. The check guide strips 9 extend upwardly at opposite sides of the series of apertures 12 and their upper ends terminate in upwardly diverging branches 13, which terminate at the ends of the elongated check receiving slot 14, as clearly shown in Figures 1 and 8. In playing the game the competing players drop 10 checks, preferably in the form of metal discs into the elongated slots 14, so it will fall by gravity down the inclined intermediate board 3, and by providing an elongated slot the players can exercise their skill in playing for the various openings 15 12, having varying values.

As the checks slide down the intermediate board 3, they are caused to take circuitous courses by engagement with the pins 10 against which they hit, and which pins deflect the checks; 20 eventually the checks will pass between some of the pins 10 and will rest upon the upwardly and outwardly inclined members 15, which extend outwardly from the apertures 12 and into engagement with the inner side of the front wall 2 as 25 clearly shown in Figure 4. The check is shown at 16 in said Figure 4. The members 15 incline downwardly and rearwardly through the apertures 12 and terminate in downwardly extending arms 17, which are secured to the rear side of the intermediate board 3 by one of the pins 10. It will be noted that the side deflecting members 9, at their lower ends, terminate in downwardly and inwardly inclined flanges or members 18, which in turn terminate adjacent the outer sides 30 of the apertures 12 so that the check will be deflected toward the aperture, and that angularly shaped deflecting flanges 19 are disposed between the lower series of apertures for preventing checks from passing below the lower series of 35 apertures. All of the checks of each player are held in the apertures 12 until the plays are completed and then the competing players estimate the values for estimating the winner. It will be noted that high numbers may be used or high 40 cards, or combinations of cards and various kinds of games may be played. Where it is desired to use the device as a fortune telling machine the check may be dropped into the device to a particular playing card aperture 12, and then the 45 player can look to the corresponding card data at the side of the board and read the fortune under said data for the particular card. These legends may be varied as desired.

Disposed within the lower end of the game board behind the intermediate board 3 is a check receiving receptacle 20, into which the checks from the various apertures 12 pass by gravity. The receptacle 20 is preferably provided with baffles 21 for preventing unauthorized persons from removing the checks from the receptacle, and the receptacle below the baffles is provided with a locked closure 22 to be opened by an authorized person.

Slidably mounted in bearing members 23 on the rear side of the intermediate board 3 are the side rods 24 of a shutter rack, and which bars are connected together by transverse shutters 25, which are normally in the lowered position as shown in Figures 3 and 4 for holding the checks 16 in the apertures 10 until after the completion of the play. It will be noted that the shutters 25 are slidably mounted on the heads 26 of the pins 10 and on the members 17 secured to the rear side of the intermediate wall 3, hence there

will not be scraping operation, nor will the shutters become stuck to the rear surface of the intermediate wall 3. The downward movement of the racks and shutters 25 carried thereby is limited by the bearing members 23, and the rack is normally forced downwardly by a coiled spring 27, anchored at 28 to the rear side of the intermediate wall 3, and at 29 to the rack. Rockably and loosely connected on pins 30 above the rack are rock levers 31, the outer ends of which are slidably connected at 32 to the upper ends of the side rods 24 of the rack. The inner ends of the rock levers 31 are pivotally connected at 33 to the vertically movable releasing rod 34 having a handle 35. After the players have made their various plays the handle 35 is forced downwardly and the rack and shutters raised for allowing the checks 16 to slide by gravity through the apertures 12.

The ends of the check box 20 are preferably 20 provided with upwardly and outwardly extending spring arms 36 adapted to engage the inner sides of the side walls of the board for guiding any checks which may fall to the side into the receptacle. The receptacle 20 may be removed from 25 the device by removing the bottom closure 37, which is preferably held in closed position by a conventional form of lock 38.

If desired the intermediate board 3 may be stamped from sheet metal as shown at 32 in Figure 7, and when so stamped the check receiving members 15 may be stamped therefrom and the apertures 12a may be formed rectangular shaped as shown in Figure 7.

From the above it will be seen that a game of chance is provided on which fortunes may be told, high number games played, as well as card games, and that any number of competing players may use the device. It will also be seen that the various checks will be held in sight of the 40 operators at all times so that the scores may be accurately ascertained after each game, and that by a single movement through the shutter rack all checks will be released simultaneously thereby allowing them to pass to the collection receptacle 20.

The invention having been set forth what is claimed as new and useful is:

1. A game board comprising a front wall, an intermediate wall and a rear wall, apertures in the intermediate wall, means for guiding checks to positions inclining downwardly and rearwardly through said apertures, check receiving arms extending upwardly and forwardly through said apertures from the rear side of the intermediate wall and adapted to receive checks and movable shutters normally forming closures for the rear sides of the apertures.

2. A game board having a plurality of apertures therethrough and adapted to be used in substantially a vertical position, check receiving members extending outwardly and upwardly through said apertures from the rear side of the board and check holding shutters carried by the rear side of the board and forming means whereby checks supported on the members in the apertures may be released and allowed to fall by gravity to the rear of the board.

3. A device as set forth in claim 2 wherein the 70 checks are held on the upwardly and outwardly extending members by vertically movable shutters slidably mounted on the rear side of the board, said upwardly and outwardly extending members having arms to the rear of the board and anchored 75

to the rear side thereof between the shutters and the rear side of the board.

4. A game board comprising a front transparent wall, an intermediate wall having check receiving apertures extending transversely therethrough, upwardly and outwardly extending check receiving members extending through the apertures and into engagement with the front wall, check deflecting pins carried by the intermediate wall and extending into engagement with the front wall and vertically movable shutters slidably mounted on the rear side of the intermediate wall and forming closures for the apertures above the upwardly and outwardly extending members.
5. A game board comprising a front transparent wall, a rear wall, an intermediate wall, a plurality of apertures extending transversely through the intermediate wall, upwardly and forwardly extending check receiving members carried by the intermediate wall and extending through the apertures thereof and means carried by the rear wall and cooperating with the rear side of the intermediate wall for bowing said intermediate wall towards the front wall in case of rearward warping of the intermediate wall.
6. A device as set forth in claim 5 including means for limiting the forward bowing of the intermediate wall by engagement with the inner side of the front wall.

7. A device as set forth in claim 5 including a plurality of check deflecting pins carried by the intermediate wall and engaging the inner side of the front wall.

8. A device as set forth in claim 5 wherein the 5 bowing means for the intermediate wall comprises screws threaded through the rear wall and cooperating with the rear side of the intermediate wall.

9. A device as set forth in claim 5 including 10 downwardly extending flanges carried by the upwardly and forwardly extending check receiving members, said flanges being secured to the rear side of the intermediate wall.

10. A device as set forth in claim 5 including a 15 vertically slidable shutter rack carried by the rear side of the intermediate wall and shutters carried by said rack and normally forming closures for the portions of the apertures above the upwardly 20 and forwardly extending check receiving members.

11. A device as set forth in claim 5 including a shutter rack for the apertures, said shutter rack being slidably mounted on the intermediate wall, 25 a shutter operating handle and rock lever connections between the handle and the rack.

HOWARD N. McDERMOTT.
